UNITED STATES PATENT OFFICE.

WILLIAM D. POMEROY, OF NORWOOD, OHIO, ASSIGNOR, BY MESNE ASSIGNMENTS, TO THE BULLOCK ELECTRIC COMPANY, A CORPORATION OF OHIO.

CONTROLLER FOR ELECTRIC MOTORS.

No. 855,972.

Specification of Letters Patent.

Patented June 4, 1907.

Application filed December 1, 1903. Renewed November 26, 1906. Serial No. 345,177.

To all whom it may concern:

Be it known that I, WILLIAM D. POMEROY, a citizen of the United States, residing at Norwood, in the county of Hamilton and State of Ohio, have invented certain new and useful Improvements in Controllers for Electric Motors, of which the following is a full, clear, and exact specification.

My invention relates to controllers for electric motors and more particularly to controllers adapted to vary the speed of a motor by changing the voltage applied thereto and operated from a multiple voltage system.

In the most modern shops of all descriptions it has become the practice to use independent electric motors for driving the various machine tools or other driven mechanisms. In connection with this class of work a wide variation of speed control is desirable, and the object of my invention is to provide means for lessening the strain upon the motor upon change of speed and to produce a gradual change in speed in passing from one step to the next.

By my invention a multiple voltage system is used, and I provide automatic means for controlling the insertion and cutting out of armature resistance. Upon each increase in potential at the terminals of the motor, resistance is inserted in the armature circuit so that the full increase in potential is not at once applied to the armature. This resistance is afterward automatically removed from the armature circuit and a predetermined interval of time is caused to elapse before this resistance is cut out, such interval of time being of sufficient duration to allow the motor to speed up to some extent. Upon cutting out the resistance a further increase in speed occurs which brings the armature to the speed of the next running step.

Further features of my invention will be disclosed in the following specification and accompanying drawing, and the novelty thereof will be definitely set forth in the appended claims.

The drawing shows a diagram of my invention.

Generators for the multiple voltage system are indicated at 1, 1' in series with each other and connected by the switch 2 to the three wire mains 3, 3', 3'', and supplying voltages which differ from each other; for example

generator 1 may give 160 volts between mains 3 and 3', and generator 1' may give 90 55 volts between mains 3' and 3''. The armature of the motor whose speed is to be varied is indicated at 4 and its field winding at 5 connected in series with the variable field resistance 6. The field winding with its resistance is 60 connected across the mains 3, 3'' by the leads 7, 8 and so receives the full voltage of both generators. In series with the armature lead 9 is the resistance 9^a. Leads to the terminals of switch 10 form a short circuit about 65 the armature resistance when said switch is closed. This switch is provided with an upwardly extending soft iron arm 11, which forms the core of the coil 12. A lower extension from the switch carries the plunger 13 70 which works in the cylinder 14, forming a dash-pot. The plunger 13 is provided with openings 15 and carries a loosely fitting flat ring 16 which normally closes the openings 15. The cylinder 14 is provided with openings 17 located equally distant from the closed bottom of the cylinder. When current passes in coil 12, the switch is raised with a comparatively slow movement as the air passes to the bottom of the plunger only by 80 leakage about the same. Just before the switch is closed, however, the plunger passes by the holes 17, permitting a free flow of air below it and the switch then closes with a sudden movement. When no current passes 85 in coil 12, the switch quickly falls, due either to the force of gravity, or spring pressure against the movable part, as preferred, the air from beneath the plunger passing freely through the holes 15 as the ring 16 is then 90 raised from its seat.

The parts above described are interconnected and also connected to the fingers 1^a, 1^b, 1^c, . . . 1^o of the controller as shown. The controller cylinder is made up of three metal 95 drums 18, 19 and 20 insulated from each other. The two upper drums control the connections to the armature and have the contacts indicated held upon lugs projecting from the body of the drum. The lower cylinder changes the field resistance and is in the form of a cylinder having cut-away portions. As the cylinder is revolved from off position the fingers 1^a, 1^b, . . . 1^o take the successive positions indicated by the lines 2^a, 2^b, 2^c, . . . 105 2^l, for forward rotation and the positions 3^a,

3^b, . . . 3ⁱ for backward rotation of the motor. For position 2^a the path of the current is as follows: from main 3^{''} to finger 1^h, contact 21, drum 19, contact 22, finger 1^f, lead 23, armature 4, lead 24, switch 10 or resistance 9^a according as said switch 10 is closed or open, leads 9 and 25, finger 1^b, contact 26, drum 18, contact 27, finger 1^d to main 3['], thus subjecting the armature of the motor to the voltage of generator 1'. For position 2^a, the field connections are from main 3, through lead 7, field 5, finger 1^o, drum 20, finger 1^j, lead 8 to main 3^{''}, thus subjecting the field to the full voltage of mains 3, 3^{''} with all of resistance 6 cut out. Connection is also made from main 3['], through coil 12 to finger 1ⁱ and drum 20, which is connected to main 3^{''} through finger 1^j, and lead 8. The coil 12 is therefore subjected to the voltage of generator 1' and switch 10 is caused to close.

In tracing the circuits below, the switch 10 will be considered to be closed, as such is its ultimate position. Should the switch be open the current will flow through the resistance 9^a instead of through said switch.

For position 2°, finger 1°, is cut out of contact with drum 20, and a section of resistance 6 is inserted in the field circuit, the field current passing from the field winding 5 to finger 1ⁿ through a section of the field resistance and then to drum 20. No other changes take place, and by thus weakening the field of the motor an increased speed is obtained. In the same way for position 2^c a still further weakening of the field takes place by inserting another section of resistance 6 in the field circuit, and in this position current passes from the field 5 through two sections of resistance to finger 1^m and drum 20.

For position 2^d the armature connections are from main 3['] to finger 1^e, contact 28, drum 19, contact 29, finger 1^f, lead 23, armature 4, lead 24, switch 10, leads 9 and 25, finger 1^b, contact 30, drum 18, contact 31, finger 1^a, to main 3. The armature of the motor is therefore subjected to the voltage of generator 1 which is greater than that of generator 1'. The field connections and those of coil 12 are the same for this position as for position 2^a, and the speed of the motor is increased by the increase in voltage applied to its armature. For positions 2^e and 2^f the only changes that take place are the weakening of the field by cutting in sections of resistance 6, as in positions 2^b and 2^c.

For position 2^g the armature connections are from main 3^{''} to finger 1^h, contact 32, drum 19, contact 33, finger 1^f, lead 23, armature 4, lead 24, switch 10, leads 9 and 25, finger 1^b, contact 34, drum 18, contact 35, finger 1^a to main 3. The armature of the motor is therefore subjected to the total voltage of both generators. The field connections and those of coil 12 are the same as for positions 2^a and 2^d, with resistance 6 cut out, and in-

creased speed is obtained by the increase in electromotive force applied to the motor armature.

For positions 2^h, 2ⁱ, 2^j, 2^k, and 2^l the connections remain the same except that sections of resistance 6 are successively cut in until it is all in circuit, in this manner successively weakening the field for increases in speed from positions 2^g to 2^l.

It will be noted that in passing from position 2^e to 2^d, and from 2^f to 2^g, at which times the change in voltage applied to the motor armature takes place, finger 1ⁱ is momentarily cut out of contact with the drum 20 and circuit through coil 12 is broken. At the instant finger 1ⁱ breaks contact with drum 20, switch 10 drops and resistance 9^a is inserted in series with the armature 4, so that when the increased voltage is applied to the armature, this resistance will prevent a too sudden rush of current with consequent strains on the motor. As coil 12 is again placed in circuit at positions 2^d and 2^g, the switch 10 will be closed and the resistance 9^a short circuited, but on account of the slow upward movement of the switch the motor will have had sufficient time to increase in speed before the switch is closed. When the controller is moved from the "off" position to the starting position 2^a, the switch 10 is closed in the same slow manner.

For reverse rotation of the motor, the fingers are in positions 3^a to 3ⁱ successively. For position 3^a the current passes from main 3^{''} to finger 1^h, contact 36, drum 19, contact 37, finger 1^g, lead 9, switch 10, lead 24, armature 4, leads 23 and 38, finger 1^e, contact 39, drum 18, contact 40, finger 1^d, to main 3[']. The armature 4 is therefore subjected to voltage of generator 1', and the armature current is reversed, while the field is the same as for position 2^a. The direction of rotation of the motor is therefore reversed and the motor operates at its slowest speed. For positions 3^b and 3^c the field strength is weakened as before. For position 3^d the circuit is as follows: main 3['], finger 1^e, contact 41, drum 19, contact 42, finger 1^g, lead 9, switch 10, lead 24, armature 4, leads 23 and 38, finger 1^e, contact 43, drum 18, contact 44, finger 1^a to main 3. For this position, although the motor has its full field strength as in position 3^a, an increased speed is obtained by reason of the armature being subjected to the voltage of generator 1. At positions 3^e and 3^f, increased speeds are obtained by weakening the field strength. For position 3^g, the connections are as follows: From main 3['] to finger 1^h, contact 45, drum 19, contact 46, finger 1^g, lead 9, switch 10, lead 24, armature 4, leads 23 and 38, finger 1^e, contact 47, drum 18, contact 48, finger 1^a to main 3, the motor in this case being subjected to the total voltage of both generators. At positions 3^h and 3ⁱ the field strength is weakened. In

passing from positions 3^c to 3^d and from 3^f to 3^g, the armature resistance 9^a is cut in to relieve the strain on the motor, as already explained with reference to passing from positions 2^c to 2^d and from 2^f to 2^g. It is therefore evident from the above description that twelve speeds forward and nine speeds in the reverse direction are obtained.

Although I have described a specific embodiment of my invention, it is evident that various modifications may be made therein without departing from the scope of the claims.

I claim as my invention:

1. The combination of a multiple voltage system, a motor having an armature resistance, a shunt about said resistance, an electro-magnetically operated switch in said shunt, a controller and connecting leads, said controller having contacts adapted to vary the voltage applied to the armature circuit and to control said electro-magnetically operated switch.

2. The combination of a multiple voltage system, a motor having an armature resistance, a shunt about said resistance, a switch in said shunt which normally tends to open, electro-magnetic means for closing said switch, a controller and connecting leads, said controller having contacts adapted to vary the voltage applied to the armature circuit and to open and close the circuit of said electro-magnetic means upon changing the voltage of the armature circuit.

3. The combination of a multiple voltage system, a motor having armature resistance, a shunt about said resistance, a switch in said shunt which normally tends to open, electro-magnetic means for closing said switch, means for retarding the closing of said switch, a controller and connecting leads, said controller having contacts adapted to vary the voltage applied to the armature circuit and to open and close the circuit of said electro-magnetic means upon changing the voltage of the armature circuit.

4. The combination of a multiple voltage system, a motor arranged to be variably connected to said system, a resistance for the motor armature circuit, a shunt about said resistance, and a remotely controlled switch in said shunt.

5. The combination of a multiple-voltage system, a motor arranged to be connected across different sets of the mains of the system, a resistance in the motor armature circuit, an electromagnetically operated switch in shunt to said resistance, and a controller for said switch.

6. The combination of a multiple-voltage system, a motor arranged to be connected across different sets of the mains of the sys-

tem, resistance in the motor armature circuit, a switch in shunt to said resistance, and a master controller for said switch from 65 which said switch is separate.

7. The combination of a multiple-voltage system, a motor, a controller arranged to connect the armature of said motor across different sets of the mains of the system, a 70 resistance in the circuit of said armature, and a switch separate from said controller but controlled thereby and in shunt to said resistance.

8. The combination of a multiple-voltage 75 system, a motor, a controller arranged to connect the armature of said motor across different sets of the mains of the system, a resistance in the circuit of said armature, and a switch separate from said controller 80 but controlled thereby and in shunt to said resistance.

9. In a switch for dynamo-electric machinery, the combination with a motor, a circuit therefor, and resistance for the circuit, 85 of means for effecting changes in the potential on the leads of the armature circuit of the motor, and means remote from the aforesaid means for cutting said resistance into and out of said circuit.

10. In a switch for dynamo-electric machinery, the combination with a motor, field and armature circuits therefor, of a controller for effecting an increase in potential of the armature circuit, and an automatic time device remote from the controller for delaying 90 the increase in potential at the armature terminals.

11. In a switch for dynamo-electric machinery, the combination with a motor, field 100 and armature circuits therefor, and resistance for the armature circuit, of a controller for varying the potential on the leads of the armature circuit, and a switch away from said controller for cutting said resistance 105 into said armature circuit for a predetermined time whenever the controller varies said potential.

12. In a switch for dynamo-electric machinery, the combination with a motor, field 110 and armature circuits therefor, and resistance for the armature circuit, of a controller for varying the potential on the leads of the armature circuit, and an electromagnetically operated switch for cutting said resistance 115 into said armature circuit for a predetermined time whenever said potential is varied.

In testimony whereof I affix my signature, in presence of two witnesses.

WILLIAM D. POMEROY.
